OIL THIEF

Application filed December 25, 1930. Serial No. 504,667.

This invention relates to devices for taking samples of the liquid contents of a container, devices of this general class, when intended for taking samples of oil, being known in the trade as "oil thieves."

An object of the invention is the provision of an improved and simplified oil thief where-
in various refinements of construction are incorporated to avoid to as great an extent as is
practically possible agitation of the liquid
of which a sample is being taken, and thereby
obtain a sample which is truly representative
of the contents of the container in the par-
ticular locality within which the oil thief is
actuated.

Another object is to provide means for in-
dicating to an operator when he has lowered
the oil thief to a predetermined distance from
the bottom of the tank, thereby enabling him
to actuate the sampler before it has been low-
ered into the sludge which is frequently pre-
sent at the bottom of such containers as oil
storage tanks.

A further object is to provide an oil thief
as described, having improved and simplified
actuating means therefor, whereby release of
the detent holding the sampler inoperative
is effected through the expedient of a trip
in the form of a tube slidably mounted upon
the means whereby the thief is lowered into
the container. This eliminates the necessity
of employing more than one cord or equiva-
lent element which must be handled by the
operator in lowering the oil thief and actuat-
ing it.

A still further object is to provide means
for positively drawing fluid into the barrel
of the oil thief and for positively expelling
the fluid therefrom after the device has been
removed from the container. In this connec-
tion, the expelling means is adapted to effi-
ciently wipe the interior surface of the barrel
and thereby avoid the danger of contaminat-
ing a later sample with material adhering to
the walls thereof.

The invention possesses other objects and
advantageous features, some of which, with
those enumerated, will be set forth in the fol-
lowing description of the invention's par-
ticular embodiment which is illustrated in

the drawing accompanying and forming a
part of the specification.

Referring to the drawing:

Fig. 1 is a vertical sectional view taken
through an oil tank, and showing an oil thief
incorporating the principles of the present
invention, disposed therein in position ready
to be released.

Fig. 2 is a view similar to Fig. 1, but show-
ing the oil thief subsequent to its release.

Fig. 3 is an enlarged vertical medial sec-
tional view of the oil thief as illustrated in
Fig. 2, portions of the figure being broken
away to reduce its length.

Fig. 4 is a horizontal sectional view taken
upon the line 4-4 of Fig. 3, with the direc-
tion of view as indicated.

Fig. 5 is an enlarged view of a portion of
the oil thief, showing the manner of inter-
engagement of the detent with the means for
holding the barrel elevated.

In terms of broad inclusion, the oil thief
of the present invention comprises a plung-
er provided with means for lowering it into
the container whose contents are to be sam-
pled, and a barrel reciprocably mounted upon
said plunger, there being means interposed
between the barrel and the plunger for hold-
ing the barrel elevated with respect thereto
until such time as the operator desires to re-
lease the holding means and permit the barrel
to drop so as to entrap a portion of the con-
tents of the fluid within which the device is
immersed. Upon completion of the down-
ward motion of the barrel with respect to
the plunger its open end seats upon a valve
adapted to close that end so as to prevent
leakage of the sample from the barrel when
the device is removed from the container.

Means are provided for positively drawing
the fluid into the open lower end of the barrel
during downward motion thereof, and addi-
tional means are employed for positively ex-
pelling the contents of the barrel in such a
manner as to effectually wipe the interior
surface of the barrel and thus remove substan-
tially all of those portions of the sample
which tend to adhere thereto. The plunger
is provided with an extension whereby the op-
erator is warned when the device has been

lowered to a predetermined distance from the bottom of the tank, thereby preventing danger of lowering the device into the sludge which frequently is present at the bottom of oil storage tanks, it being understood that it is desirable under most circumstances to take samples of the oil without any of the sludge in suspension therein. However, this extension of the barrel is removable, so as to permit sampling the sludge itself if desired. The means for releasing the barrel to permit it to drop and thus entrap a sample of the oil is in the form of a tube slidable upon the suspending means, which may be dropped thereupon after the sampler has been lowered to the desired depth within the tank, and thus release the means whereby the barrel is held elevated upon its plunger.

More specifically, the oil thief of my invention comprises a plunger, indicated in its entirety at 6, this plunger including a rod 7 having an eye 8, preferably removably secured to its upper end. For this purpose, the eye 8 is formed in a ferrule 9 threadedly receivable upon the upper end of the rod 7. The eye 8 provides convenient means for attaching a suspending member such as a cord 11 thereto, this suspending means being provided with preferably a spring snap 12 which may be attached to the eye 8 and disengaged therefrom substantially instantaneously.

A barrel 16 encircles the plunger 6 and is reciprocably mounted thereupon through the expedient of a guide bushing 17 held at a material distance above the upper end of the barrel 16 by a plurality of brackets 18. Both ends of the barrel 16 are open, communication between the interior of the barrel 16 and the exterior thereof being established between the several brackets 18. The rod 7 of the plunger 6 carries a pair of opposed cup-washers 21 and 22, separated by preferably a pair of disks 23 and 24, although if desired a single disk may be employed, the thickness of which is equal to the total thickness of the two disks 23 and 24, so as to hold the two cup-washers 21 and 22 spaced properly. These cup-washers 21 and 22 are reinforced by external disks 26 and 27, respectively, the entire assembly of disks and cup-washers being compressed between a pair of spaced nuts 28 and 29 threaded onto the rod 7.

A preferably tapered valve seat 31 is formed at the lower end of the barrel 16, encircling the opening 32 therein, whereby communication is established with the interior of the barrel. Cooperative with this valve seat 31 is a valve 33 in the form of a head rigidly mounted upon the rod 7 in any suitable manner. The parts are so proportioned and arranged that when the barrel 16 drops to its lowest extreme of movement with respect to the plunger 6 the seat 31 will engage upon the valve 33 and effectually close the

lower end 32 of the barrel 16, so as to prevent leakage therewith of any liquid entrapped within the barrel 16.

Means are provided for holding the barrel 16 elevated, i. e., at its uppermost extreme of movement with respect to the plunger 6, until the operator desires to actuate the device. A detent 36 is pivotally mounted upon the annulus 37 within which the bushing 17 is rigidly secured, this annulus 37 preferably being integral with the several brackets 18. Preferably, a pair of spaced lugs 38 extend laterally from the annulus 37, with the detent 36 pivotally mounted therebetween by means of a pivot pin 39. The upper end of the detent 36 is defined by an edge 41 which inclines upwards and outwards, this edge 41 terminating in a relatively sharp point 42 at the intersection of the edge 41 with a shoulder 43, which is adapted to engage over an annular flange 44 carried by the rod 7 of the plunger 6. This flange 44 is preferably a cup-shaped washer clamped between the ferrule 9 and a nut 46 threaded upon the rod 7 in such position that when the shoulder 43 of the detent 36 is engaged in this manner with the flange 44 the barrel 16 will be retained thereby in its upper extreme of movement upon the plunger 6. In view of the fact that the flange 44 is annular and continuous throughout 360°, the detent 36 can be engaged therewith, without having to rotate the barrel 16 to any special position with respect to the plunger 6. Moreover, the pin 39, whereby the detent 36 is pivoted upon the lugs 38, is disposed below, and at a greater distance from the axis of the entire device, than the center of gravity of the detent 36, with the result that the detent is continually urged by gravity so as to swing its upper end inwards, i. e., toward the left, as viewed upon Figs. 3 and 5. A projection 47 on the lower end of the detent 36 is adapted to engage one of the brackets 18 and prevent the detent from swinging outwards so as to move the center of gravity thereof beyond the pivot pin 39.

A tubular trip 51 is slidably mounted upon the cord 11, being of such dimensions that it is adapted to slip downwards thereupon past the clip 12 and ferrule 9, so as to permit the lower end 52 of the trip 51 to engage the inclined upper edge 41 of the detent 36, forcing the detent outwards to disengage it from the flange 44. Obviously, when such disengagement occurs the barrel 16 will be permitted to drop until the valve seat 31 at its lower end seats upon the valve 33. The lower end 52 of the trip 51 is expanded to define a bell mouth, the purpose being to prevent the possibility of cutting or abrading the cord 11 by the relatively sharp edge which might otherwise be present at the lower end of the trip 51. Furthermore, this bell mouth facilitates the tubular trip 51 in dropping past the

obstructions offered by the clip 8 and ferrule 9.

Means are provided for indicating to the operator when the oil thief has been lowered to a predetermined distance from the bottom 56 of a tank 57, or other receptacle the liquid contents 58 of which are to be sampled. For this purpose a pin 59 is removably attached to the lower end of the rod 7 of the plunger 6. Preferably, the pin 59 has a socket 61 rigidly secured to its upper end and threadedly engageable upon the lower end 62 of the rod 7 which extends through the valve 33. The purpose of employing this pin 59 is to provide a relatively small projection at the lower end of the oil thief which is capable of penetrating the sludge 63 frequently present at the bottom of an oil tank 57, so as to warn the operator when the oil thief has been lowered to a position adjacent the bottom 56 of the tank 57 but clear of the sludge 63. In view of the fact that the pin 59 is of relatively small cross sectional area, it is capable of penetrating the sludge 63 without causing undue agitation thereof, with the result that when the trip 51 is dropped to release the detent 36 the barrel 16 will be permitted to drop, thereby entrapping a quantity of the liquid contents 58 of the tank 57 containing little or none of the sludge 63, which would not be the case if the oil thief were lowered until the valve 33 made contact with and penetrated the sludge 63. Even if the oil thief were elevated after such penetration by the valve 33 of the sludge 63, the sludge would be so agitated that at least some of it would in all probability be present in that portion of the oil or other liquid contents 58 of the tank that a true sample could not be obtained. Obviously, the device may be employed to take samples of the contents of a container at any desired point between the bottom of the container and the upper surface of the liquid. The operator may judge the depth to which the oil thief has been lowered by keeping track of the amount of cord 11 paid out in lowering the device into the tank, and after the desired depth has been attained he should then release the tubular trip 51, which will disengage the detent 36 in the manner explained hereinabove, thereby actuating the oil thief to take its sample.

Owing to the presence of the cup-washer 27, the downward motion of the barrel 16 with respect to the plunger 6 will produce an area of low pressure within the barrel 16 below the cup washer 27, serving to effectually draw fluid into the barrel 16 and thus insure taking a complete sample. Upon completion of the downward motion of the barrel the valve 33 and the cup-washer 22 cooperate to retain the entrapped liquid within the barrel 16, even after the oil thief has been withdrawn from the tank 57. However, when it is desired to release the sample from

the barrel 16, it is necessary merely to raise the barrel upon the plunger, whereupon the cup-washer 21 will positively drive the contents of the barrel therefrom, effectually wiping the interior surface of the barrel 16 to remove substantially the entire contents thereof. This is considered an important improvement over previously employed oil thieves, inasmuch as it eliminates the necessity of cleansing the oil thief before taking a subsequent sample, because there will not be a sufficient quantity of liquid adhering to the interior surface of the barrel 16, owing to the above described action of the cup-washer 21, to materially effect the constituency of a later sample taken by the same device.

Another improvement effected by means of the oil thief of the present invention lies in the absence of agitation of the liquid 58 being sampled upon actuation of the sampling device. When the barrel 16 drops, the liquid both inside and outside thereof remains stationary and the barrel 16 merely moves downwards with respect thereto, and with respect to the plunger 6. The cross sectional area of the walls of the barrel 16 is relatively small, with the result that substantially no motion of the liquid is caused by this motion of the barrel, which, of course, is conducive to taking a more accurate sample. The relatively small size of the entire device is also of importance, inasmuch as it permits lowering the oil thief into a tank 57 or other container through a relatively small aperture in the top of that container.

It is to be understood that the details of the invention as herein disclosed, are subject to alteration within the spirit or scope of the appended claims.

I claim:

1. A sample taking device, comprising a plunger, suspending means connected thereto, a barrel encircling said plunger and reciprocably mounted thereupon, a detent pivotally mounted on said barrel, means on said plunger engageable by said detent to hold said barrel elevated with respect to said plunger, and means slidable on said suspending means for releasing said detent, said detent being mounted for pivotal movement about an axis spaced further from said engageable means than the center of gravity of said detent in its extreme released position, whereby the detent is continually urged toward engaging position by gravity.

2. A sample taking device, comprising a plunger, suspending means connected thereto, a barrel encircling said plunger and reciprocably mounted thereupon, a detent pivotally mounted on said barrel and having an upper edge inclining upwards and outwards, means on said plunger engageable by said detent to hold said barrel elevated with respect to said plunger, and a tubular trip slidably upon said suspending means and engageable

able with said inclined edge to move the detent from engaging position when the trip is dropped upon said suspending means.

3. A sample taking device, comprising a plunger, suspending means connected thereto, a barrel encircling said plunger and reciprocably mounted thereupon, a detent pivotally mounted on said barrel and having an upper edge inclining upwards and outwards, means on said plunger engageable by said detent to hold said barrel elevated with respect to said plunger, and a tubular trip slideable upon said suspending means and engageable with said inclined edge to move the detent from engaging position when the trip is dropped upon said suspending means, the lower end of said trip being expanded to define a bell mouth.

4. A sample taking device, comprising a plunger, suspending means connected thereto, a barrel encircling said plunger and reciprocably mounted thereupon, a detent pivotally mounted on said barrel and having an upper edge inclining upwards and outwards, a continuous annular flange on said plunger engageable at any portion of the periphery thereof by said detent to hold said barrel elevated with respect to said plunger, and a tubular trip slideable upon said suspending means and engageable with said inclined edge to move the detent from engaging position when the trip is dropped upon said suspending means.

In testimony whereof I have signed my name to this specification.

OSCAR W. PEARCE.
